UNITED STATES PATENT OFFICE.

FRANK J. MEYER, OF JAMAICA, NEW YORK, ASSIGNOR TO P. L. ANDREWS CORPORATION, A CORPORATION OF NEW YORK.

FOLDING CARTON OR CONTAINER.

Application filed February 8, 1924. Serial No. 691,340.

To all whom it may concern:

Be it known that I, FRANK J. MEYER, a citizen of the United States, residing at Jamaica, Long Island, in the county of Queens and State of New York, have invented certain new and useful Improvements in Folding Cartons or Containers; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in paper cartons or containers; and, the invention has reference, more particularly, to a novel carton or container for holding and dispensing rolled sheet material, and said carton or container being of the folding type which is made up from a single piece of card-board or the like.

The invention has for its principal object to provide a novel carton or container in which may be enclosed a roll of sheet material; said carton or container having a novel means through which the free end of the enclosed roll of sheet material may issue and through which it may be drawn to dispense desired lengths of such sheet material for detachment from the main body thereof. With such end in view, the novel carton or container comprises, in combination with a main body member and end flaps scored and folded to form the longitudinal sides and ends of the carton or container, certain additional foldable members adapted to provide a novel delivery means having a guiding exit passage through which may issue the free end of the roll of sheet material enclosed within the carton or container; the free longitudinal edge of said novel delivery means also providing a means against which the withdrawn end portion of the sheet material may be torn or severed to detach the same from the main body of said rolled sheet material remaining within the carton or container. The novel carton or container is adapted to hold and dispense from a roll thereof such materials as waxed or paraffine paper, paper toweling, paper for napkins, toilet paper, wrapping paper or any other similar products.

Other objects of this invention, not at this time more particularly enumerated, will be clearly understood from the following detailed description of the same.

With the various objects of this invention in view the same consists, primarily, in the novel carton or container for holding and dispensing rolled sheet material hereinafter set forth; and, the invention consists, furthermore, in the novel arrangements and combinations of the various devices and parts, as well as in the details of the construction thereof, all of which will be hereinafter more fully described in the following specification, and then finally embodied in the claims appended thereto.

The invention is clearly illustrated in the accompanying drawings, in which:

Figures 1, 2 and 3 are respectively perspective views of the complete carton or container, made according to and embodying the principles of this invention, said views showing various ways of positioning the carton or container for use when dispensing the enclosed sheet material therefrom.

Figure 4 is a plan view of the blank adapted to be folded so as to provide the novel rolled sheet material holding and dispensing container shown respectively in Figures 1, 2 and 3.

Figure 5 is a plan view of the novel carton or container with the delivery means partly made up; and Figure 6 is a transverse section, taken on line 6-6 in Figure 5.

Figure 7 is a plan view of the novel carton or container completed; and Figure 8 is a transverse section, taken on line 8-8 in Figure 7.

Figure 9 is a fragmentary perspective view of a plurality of the novel cartons or containers, illustrating the manner in which the same are arranged and interrelated together when packing the same for shipment or carriage.

Similar characters of reference are employed in all of the above described views, to indicate corresponding parts.

Referring now to the drawings and more especially to Figure 4 thereof, the reference character 1 indicates a paper or cardboard blank from which the novel carton or container is formed. The said blank is provided with a series of longitudinal scores or scribes, as indicated by the dotted lines 2,

3, 4, 5 and 6 to provide intermediate panels 7, 8, 9 and 10 which, when the blank is folded along the lines of said scores or scribes, form the sides of the main carton 5 or container. Extending outwardly from each end of the panel 7 are foldable end tabs or tongues 11, the junctures of which with the extremities of said panels 7 are defined by the scores or scribes 12; and, in like manner, extending outwardly from each end of the panel 9 are similar foldable end tabs or tongues 13, the junctures of which with the extremities of said panel 9 are defined by the scores or scribes 14. Also extending 10 outwardly from each end of the panel 10 are foldable exterior end tabs or tongue 15, the junctures of which with the extremities of the panel 10 are defined by the scores or scribes 16, and connected with the free end 15 of each exterior tab or tongue 15 is a tuck-flap 17, the juncture of which with said exterior tab or tongue 15 is defined by the score or scribe 18.

Extending along the outer longitudinal scored edge of the panel 7 is a top delivery guide panel 19, which in turn is provided along its outer longitudinal side with a longitudinal combined reenforcing and pocket forming flap 20, the juncture of which with 25 said top delivery guide panel 19 is defined by the score or scribe 21. The body of said top delivery guide panel 19 is provided in a suitable location intermediate its ends with an opening or slot 22, and said flap 20 30 is also provided with a corresponding opening or slot 23. Said flap 20 is further provided, adjacent to each end thereof, with a transverse slit 24.

Extending along the outer longitudinal scored edge of the panel 10 is a bottom delivery guide panel 25. Extending outwardly from each end of the bottom delivery guide panel 25 are foldable lock-tongues 26, the junctures of which with the 40 extremities of said panel 25 are defined by the scores or scribes 27. The side edges of said lock-tongues 26 are preferably converging toward the outer free ends thereof, and each tongue is provided at one of its 45 side edge portions with a laterally projecting lock-nosing 28 which provides a shoulder or stop 29, the purpose of which will subsequently appear. The body of said bottom delivery guide panel 25 is provided 50 intermediate its ends with an opening or slot 30.

The blank, thus above described in detail, is set up to form the novel carton or container in the following manner. The panels 60 7, 8, 9 and 10 are folded along the lines of intermediate scores or scribes 3, 4 and 5, so as to be successively positioned at right angles, thus forming the four longitudinal sides of the carton or container which 65 close a longitudinal storage or holding space

or interior 31, in which may be disposed a roll 32 of the sheet material it is desired to dispense from said carton or container. The said carton or container is closed at its ends by first turning or folding inwardly, across the open ends of the holding space or interior 31, the respective end tabs or tongues 11 and 13, and then by turning or folding over the exterior end tabs or tongues 15, with the tuck-flaps 17 inserted intermediate the ends 70 of the opposite panel 8 and the adjacent edges of the folded tabs or tongues 11 and 13. When the formation of the carton or container is thus far completed, the bottom delivery guide panel 25 is left to extend outwardly from one lower longitudinal edge or corner of the main body, and in the plane of the panel 10. The top delivery guide panel 19 is turned outwardly to extend at right angles to the outer face of the panel 7, 80 and thus caused to over-lie the bottom delivery guide panel 25 in a plane parallel to the latter. The combined reenforcing and pocket forming flap 20 is thereupon turned upwardly and inwardly so as to be doubled 90 back across the outer side of said top delivery guide panel 19. The respective longitudinal marginal portions of said flap 20 are provided, on the face thereof which is to meet and over-lie said top delivery 95 guide panel 19, with longitudinal strips or zones of adhesive material, whereby said flap 20 is caused to adhere to and be thus permanently secured to the top delivery 100 guide panel 19, so that not only is the latter 105 reinforced and stiffened, but an internal pocket intermediate the said parts is formed, with which the transverse slits 24 communicate. The arrangement or mutual cooperative relation thus established between the bottom delivery guide panel 25 and top delivery guide panel 19, provides an intermediate passageway or guideway 33 which is open at its outer side and which communicates at its inner side with the interior 110 31 of the completed carton or container. The lateral ends of said passageway or guideway 33 are closed, and at the same time said top and bottom delivery guide 115 panels 19 and 25 are operatively interlocked together, by turning upwardly and inwardly the lock-tongues 26, and inserting their free ends respectively through the respective slits 24, to enter the same in the pocket intermediate the top delivery 120 guide panel 19 and the flap 20, with the lock-nosings 28 internally disposed in said pocket, and the shoulders or stops 29 respectively interlocked against one end respectively of each slit 24. When the top 125 and bottom delivery guide panels 19 and 25 are thus operatively interconnected, the openings or slots 22 and 23 of the panel 19 and flap 20 will be registered together to provide access to material extending 130

through the pasageway or guideway 33, and at the same time the opening or slot 30 of the panel 25 will be alined opposite the registered openings or slots 22 and 23. The 5 free end portion 34 of the roll of sheet-material disposed within the interior 31 of the carton or container is extended or entered within so as to pass outwardly through the passageway or guideway 33.

10 The novel carton or container, constructed as above described, provides a very convenient means for holding and dispensing portions of sheet material of any desired length from a roll of latter enclosed within the 15 said carton or container, while at the same time the carton or container adequately protects the roll of sheet material against physical injury and from being soiled or in any way contaminated. The carton or container 20 may be variously positioned for use, when dispensing the sheet material therefrom. For example, as shown in Figure 1, it may be laid upon a counter or table, with the delivery guide means projecting from the bottom side thereof and lying flatwise upon the surface of the counter or table. When 25 so disposed, and it is desired to withdraw a portion of the sheet material therefrom, the user engages the free end portion 34 of said 30 sheet material, which is lodged within the passageway or guideway 33, by inserting the finger through the registered slots 22 and 23 and pressing the paper against the surface of the counter or table while at the same 35 time moving forward the finger toward the discharge end of said passageway or guideway 33. Such operation slides the extremity of the free end portion 34 of the sheet material outwardly through the discharge end of the passageway or guideway 33, to expose 40 the same to the grasp of the user, who upon grasping the outwardly projecting extremity may pull outward the sheet material, which will be caused to unroll from the roll 45 32, until a desired length of the same has issued from the discharge end of said passageway or guideway 33. The user may then tear off the withdrawn portion of the sheet material, by lifting the same and tearing 50 the same against the outer edge portion of the delivery means, as illustrated in Figure 1. The carton or container may be laid upon the edge portion or ledge of a counter, so that the delivery means depends therefrom and is vertically disposed against a 55 perpendicular wall surface, as shown in Figure 2. In such case the user inserts the finger through the opening or slot 30 and presses the free end portion 34 of the sheet material through the registered openings or 60 slots 22 and 23 and against the wall surface while moving the finger downward, to thus eject from the discharge end of the passageway or guideway the extremity of the sheet 65 material, so that the latter may be grasped

and the material unrolled and withdrawn, and then torn off against the outer edge portion of delivery means.

If desired the carton or container may be supported in any suitable manner, and by 70 suitable means, against a perpendicular wall surface, in the manner shown in Figure 3, and then the operations of ejecting and withdrawing the sheet material may be carried out in substantially the same manner 75 as already above described.

When it is desired to pack together a number of the novel cartons or containers with their contents, so that the same may be shipped or transported, the same are arranged as shown in Figure 9, wherein it will be seen that the same are arranged in pairs or couples with their normally outwardly projecting delivery means respectively turned upward and downward and 80 overlapped to lie against the sides of the main bodies thereof. It will be noticed that when thus arranged, the cartons or containers may be compactly grouped together for enclosure in a rectangular package or 85 carrying container, and that all parts are adequately protected against injury during 90 transit.

I am aware that some changes may be made in the general arrangements and combinations of the various devices and parts, as well as in the details of the construction thereof, without departing from the scope of this invention as set forth in the foregoing specification, and as defined in the 95 claims. Hence, I do not limit this invention to the exact arrangements and combinations of the several devices and parts, as described in the above specification, nor do I confine myself to the exact details of the construction of said parts, as illustrated in the accompanying drawings.

I claim:—

1. A carton or container, comprising a box-like main body having side and end 110 members to enclose a main compartment for holding a roll of sheet material; a bottom delivery guide panel; a top delivery guide panel; said delivery guide panels respectively projecting outwardly from contiguous longitudinal edges of two adjacent side members of said main body so as to overlie one another, to provide intermediate the same a passageway leading outwardly from said main compartment through which the free 115 end portion of said roll of sheet material may be withdrawn; one of said delivery guide panels having at each transverse end a foldable lock tongue; and means connected with the transverse ends of the other delivery 120 guide panel with which said lock tongues cooperate to thus close the transverse ends of said passageway.

2. A carton or container, comprising a box-like main body having side and end 130

4

members to enclose a main compartment for holding a roll of sheet material; a bottom delivery guide panel; a top delivery guide panel; said delivery guide panels respectively projecting outwardly from contiguous longitudinal edges of two adjacent side members of said main body so as to overlie one another, to provide intermediate the same a passageway leading outwardly from said main compartment through which the free end portion of said roll of sheet material may be withdrawn; one of said delivery guide panels having at each transverse end a foldable lock tongue; means connected with the transverse ends of the other delivery guide panel with which said lock tongues cooperate to thus close the transverse ends of said passageway; and at least one of said delivery guide panels having intermediate its ends an opening giving access to the sheet material entered in said passageway.

3. A carton or container, comprising a box-like main body having side and end members to enclose a main compartment for holding a roll of sheet material; a bottom delivery guide panel; a top delivery guide panel; said delivery guide panels respectively projecting outwardly from contiguous longitudinal edges of two adjacent side members of said main body so as to overlie one another, to provide intermediate the same a passageway leading outwardly from said main compartment through which the free end portion of said roll of sheet material may be withdrawn; said top delivery guide panel having a reenforcing flap connected with its outer longitudinal edge and doubled back upon the same; said reenforcing flap having transverse slits adjacent to each end thereof; means for securing said reenforcing flap to the body of said top delivery guide panel so as to provide a space intermediate the former and the latter beneath said slits; said bottom delivery guide panel having at each transverse end a foldable lock-tongue respectively engaged in the respective slits of said reenforcing flap to thus close the transverse ends of said passageway; and means connected with the transverse ends of the other delivery guide panel with which said lock tongues cooperate to thus close the transverse ends of said passageway.

4. A carton or container, comprising a box-like main body having side and end members to enclose a main compartment for holding a roll of sheet material; a bottom delivery guide panel; a top delivery guide panel; said delivery guide panels respectively projecting outwardly from contiguous longitudinal edges of two adjacent side members of said main body so as to overlie one another, to provide intermediate the same a passageway leading outwardly from said main compartment through which the free end portion of said roll of sheet material may be withdrawn; said top delivery guide panel having a reenforcing flap connected

with its outer longitudinal edge and doubled back upon the same; said reenforcing flap having transverse slits adjacent to each end thereof; means for securing said reenforcing flap to the body of said top delivery guide panel so as to provide a space intermediate the former and the latter beneath said slits; said bottom delivery guide panel having at each transverse end a foldable lock-tongue respectively engaged in the respective slits of said reenforcing flap to thus close the transverse ends of said passageway; and at least one of said delivery guide panels having intermediate its ends an opening giving access to the sheet material entered in said passageway.

5. A carton or container, comprising a series of interconnected side panels adapted to be folded successively at right angles one to another to form a main compartment for holding a roll of sheet material, certain of said side panels having connected with their ends foldable tongues adapted to close the ends of said main compartment; a top delivery guide panel; a bottom delivery guide panel; said delivery guide panels being respectively connected with the outer edges of outlying side panels which, when the carton is folded into set-up arrangement, are contiguous but separated one from the other, whereby said guide panels extend outwardly from one longitudinal corner of the carton so as to overlie one another to provide an intermediate passage leading outwardly from said main compartment, and through which the free end portion of said roll of sheet material may be withdrawn; one of said delivery guide panels having at each transverse end a foldable lock-tongue; and means connected with the transverse ends of the other delivery guide panel with which said lock tongues cooperate to thus close the transverse ends of said passageway.

6. A carton or container, comprising a series of interconnected side panels adapted to be folded successively at right angles one to another to form a main compartment for holding a roll of sheet material, certain of said side panels having connected with their ends foldable tongues adapted to close the ends of said main compartment; a top delivery guide panel; a bottom delivery guide panel; said delivery guide panels being respectively connected with the outer edges of outlying side panels which, when the carton is folded into set-up arrangement, are contiguous but separated one from the other, whereby said guide panels extend outwardly from one longitudinal corner of the carton so as to overlie one another to provide an intermediate passage leading outwardly from said main compartment, and through which the free end portion of said roll of sheet material may be withdrawn; one of said delivery guide

- panels having at each transverse end a foldable lock-tongue; means connected with the transverse ends of the other delivery guide panel with which said lock tongues cooperate to thus close the transverse ends of said passageway; and at least one of said delivery guide panels having intermediate its ends an opening giving access to the sheet material entered in said passageway.
- 10 7. A carton or container, comprising a series of interconnected side panels adapted to be folded successively at right angles one to another to form a main compartment for holding a roll of sheet material, certain 50 of said side panels having connected with their ends foldable tongues adapted to close the ends of said main compartment; a top delivery guide panel; a bottom delivery guide panel; said delivery guide panels being 55 respectively connected with the outer edges of outlying side panels which, when the carton is folded into set-up arrangement, are contiguous but separated one from the other, whereby said guide panels extend outwardly from one longitudinal 60 corner of the carton so as to overlie one another to provide an intermediate passage leading outwardly from said main compartment, and through which the free end portion of said roll of sheet material may be withdrawn; said top delivery guide panel having a reenforcing flap connected with its outer longitudinal edge and doubled back upon the same; said reenforcing flap 65 having transverse slits adjacent to each end thereof; means for securing said reenforcing flap to the body of said top delivery guide panel so as to provide a space intermediate the former and the latter beneath 70 said slits; said bottom delivery guide panel having at each transverse end a foldable lock-tongue respectively engaged in the respective slits of said reenforcing flap to thus close the transverse ends of said passageway; and at least one of said delivery guide panels having intermediate its ends an opening giving access to the sheet material entered in said passageway.
- 35 In testimony, that I claim the invention 85 set forth above I have hereunto set my hand this 6th day of February, 1924.
- 40 8. A carton or container, comprising a
- 45
- series of interconnected side panels adapted to be folded successively at right angles one to another to form a main compartment for holding a roll of sheet material, certain 50 of said side panels having connected with their ends foldable tongues adapted to close the ends of said main compartment; a top delivery guide panel; a bottom delivery guide panel; said delivery guide 55 panels being respectively connected with the outer edges of outlying side panels which, when the carton is folded into set-up arrangement, are contiguous but separated one from the other, whereby said guide panels extend outwardly from one longitudinal 60 corner of the carton so as to overlie one another to provide an intermediate passage leading outwardly from said main compartment, and through which the free end portion of said roll of sheet material may be withdrawn; said top delivery guide panel having a reenforcing flap connected with its outer longitudinal edge and doubled back upon the same; said reenforcing flap 65 having transverse slits adjacent to each end thereof; means for securing said reenforcing flap to the body of said top delivery guide panel so as to provide a space intermediate the former and the latter beneath 70 said slits; said bottom delivery guide panel having at each transverse end a foldable lock-tongue respectively engaged in the respective slits of said reenforcing flap to thus close the transverse ends of said passageway; and at least one of said delivery guide panels having intermediate its ends an opening giving access to the sheet material entered in said passageway.
- 45
8. A carton or container, comprising a
